Attorneys.

UNITED STATES PATENT OFFICE

JOHN W. SHERA, OF CHICAGO, ILLINOIS, ASSIGNOR TO AMERICAN FLANGE & MANUFACTURING COMPANY, OF CHICAGO, ILLINOIS, A CORPORATION OF ILLINOIS

TOOL

Application filed August 28, 1931. Serial No. 559,879.

My invention relates to an expanding tool, the tool of my invention being of particular service in connection with sealing devices for metal containers, though its use is not necessarily limited thereto.

The principal object of my invention is to provide an expanding tool which is simple in construction, easily handled, and efficacious in use.

Another object of my invention is to provide an expanding tool which will properly adjust the sealing device in sealing position while the device is being expanded.

More particularly the device embodying my invention is peculiarly adapted for use in forming a bead on a seal which is held on its seat by the tool during the beading operation.

The tool includes a body portion adapted to be screwed into the threaded bushing intended to be sealed. The seal is in the form of a cup which has a seat adapted to be held against another seat by the tool body. At the lower end of the body are expansible segments operated by a handle through a shaft.

After the body is screwed into position the handle is turned relative to the body to move the segments radially and thus form a bead on the seal to lock the latter in tight closure condition.

The above and other objects of my invention will become more apparent in connection with the following description taken in conjunction with the accompanying drawing, in which:

Fig. 1 is a cross section through a bushing and sealing device, with part of the container wall shown in section and the closure plug indicated by dotted lines;

Fig. 2 is a vertical section taken through the expanding tool embodying my invention;

Fig. 3 is a top plan view of the tool, and

Figs. 4 and 5 are cross sections taken on the line 4—4 of Fig. 2, the segments being shown in normal condition in Fig. 4, and in expanded condition in Fig. 5.

The form of work illustrated and in conjunction with which the tool of my invention may be employed will be first described.

Referring to Figs. 1 and 2, I have shown part 50 of a sheet metal wall 6 of a container such

as a steel barrel. This wall is formed with a depending rim 7 which surrounds a circular hole formed in the wall. An internally threaded bushing 8 is snugly received within this hole, this bushing being shown with an outwardly curled inner edge portion 9 which grasps the inner end of the aforesaid rim. The bushing is provided with a circumscribing flange 10 which is tightly seated upon the container wall. A closure plug 11 (shown in dotted lines in Fig. 1) is screwed within the bushing and is provided with a flange 12 which laps the flange 10. The entire sealing structure comprises two thin metallic parts,—namely a seating member 14 and a closure cup 15, as shown in my copending application, Serial No. 556,190, filed August 10, 1931. The member 14 is of cylindrical shape and has an upper cylinder portion 16 crimped around the curled end 9 of the bushing, an intermediate seat portion 17, and a lower reduced cylindrical portion 18. The cup 15 is mounted in the opening defined by the cylindrical portion 18 and has a friction fit therewith. The upper edge of the cup 15 is rolled to provide an annular pocket in which a gasket 20 of any suitable material is confined. The cup is provided with a circumscribing bead 21 below the cylindrical portion 18 to lock the cup in tight closure position and prevent removal of the cup without detection. The tool embodying my invention is adapted to force "home" the cup and form the bead 21.

The tool illustrated is inclusive of a central body 23 through the center of which extends a vertical shaft 24. The upper end of the shaft just above the body is square and receives a square opening in the center of a handle 25 which carries a hand knob 26. The handle is held in place on the shaft by a washer and nut 27, the latter being screwed on to a reduced threaded extension 28 of the shaft. The lower end of the shaft has four flat sides 29 and rounded corners 30, forming in effect four cams. The upper ends of the corner portions engage the bottom of the body to prevent movement of the shaft axially upward with respect to the body.

The lower end of the body 23 has a circu-

lar recess providing a circumscribing rim 32 within which are mounted the upper portions of four expanding segments 33. Each of the latter are segmental in cross section 5 and their inner flat surfaces form a square as best shown in Fig. 4. The lower ends of the segments form a cylindrical flange 34 divided into sections, preferably four, and the upper outer corner of the flange is beveled 10 as at 35 to form an expanding edge 36. Each segment 33 is held on the body 23 by its individual screw 37 which is screwed into a threaded opening in the segment and has its opposite end extending into a hole 38 in the 15 rim 32. The segments 33 are provided with two grooves 39 forming circumscribing channels in which are mounted coiled springs 40. The screw 37 may be a plain pin secured at one end either in the housing or segment.

20 The body 23 is provided with screw threads 42 and a series of closely spaced holes 43. A knurled adjustable ring 44 is screwed on to the threads of the body and carries a screw 45 having its head portion in threaded 25 engagement with a hole in the ring and its reduced inner end adapted to project in the holes 43.

The handle 25 carries a plunger 48 having a knurled finger button 49 screwed on its 30 upper end and having an enlarged head 50 at its lower end. A coiled spring 51 surrounding the plunger and mounted in a recess in the handle is compressed between the upper end of the recess and the head 50. 35 The upper end of the body 23 is provided with four equally spaced recesses 52 into which the head 50 is adapted to engage.

In applying the sealing cup 15 it is dropped within the cylindrical portion 18 of the seal 40 seating member 14. The body 23 is then applied to the bushing 8 and the tool is turned by the knob 26 so that the threads on the body and the bushing cause to move the lower edge of the rim 32 of the body against the 45 upper edge of the cup 15 and thus press the gasket 20 against the seat 17. The ring 44 is so adjusted that when the gasket 20 is properly seated the lower edge of the ring engages the top of the bushing and the 50 tool can be turned no further. The ring 44 may be adjusted and locked in adjusted position by the screw 37 to accommodate varying conditions, such as variations in manufacture. As the ring 44 constitutes a 55 stop, proper seating of the cup is assured and there is no danger that excessive pressure will be exerted on the cup with attendant distortion of the sealing device.

After the body is screwed into the bushing 60 as just described, the plunger 48 is pulled upwardly by the button 49, to move the lower end of the plunger out of one of the holes 52 whereupon the handle 25 is given a quarter turn relative to the body 23, the spring 65 51 being adapted to cause the lower end of

the plunger to engage in the next hole. Obviously this movement of the handle relative to the body rotates the shaft 24 relative to the segments 33. During this movement of the handle the body cannot rotate in the same 70 direction because of the engagement of the ring 44 with the bushing. This relative movement between the shaft and body causes the cams on the lower end of the shaft to separate the segments radially as shown in Fig. 75 5, the handle being at the time midway between two holes 52. As the handle moves the remainder of its quarter turn the springs 40 move the segments back to their normal position shown in Fig. 4. The tool is then 80 removed.

It will be seen that when the segments are operated by the cams, their edges expand the lower edge of the cup 15 to form the bead 21 shown in Fig. 1. The bead engages against the lower edge of the cylindrical member 14 of the sealing device to lock the cup in place and maintain the gasket 20 in proper seating condition. The seal is virtually destroyed when it is broken and it cannot be removed with a screw driver or other tool and then be replaced without detection.

Changes may be made without departing 95 from the invention.

I claim:

1. In a tool of the class described for expanding a seal for a threaded bushing, the combination of a threaded body, a handle on said body for screwing said body into said bushing, and expanding means on said tool and operated by said handle after the body has been screwed into said bushing to form a bead on said seal.

2. In a tool of the class described for 105 pressing a seal for a threaded bushing against its seat and forming a bead on the seal, the combination of a threaded body adapted to be screwed into said bushing to press said seal against its seat, expanding means carried by said body, and a handle adapted to be turned after the body is screwed into said bushing to cause said expanding means to form the bead on said seal.

3. In a tool of the class described for 115 pressing a seal for a threaded bushing against its seat and forming a bead on the seal, the combination of a threaded body adapted to be screwed into said bushing to press said seal against its seat, expanding means carried by said body, a handle adapted to be turned after the body is screwed into said bushing to cause said expanding means to form the bead on said seal, and means limiting the screwing movement of the body into 120 the bushing.

4. In a tool of the class described for pressing a seal for a threaded bushing against its seat and forming a bead on the seal, the combination of a threaded body adapted to be 130

screwed into said bushing and adapted to press said seal against its seat, an adjustable ring on said body adapted to act as a stop to limit the movement of said body in said bushing, a handle on said body, a latch between said body and handle to permit said handle to turn the body and also to move relative thereto, a shaft operated by said handle when the latter is moved relative to the body, and 10 expanding segments operated by said shaft to form said bead.

5 5. In a tool of the class described for forming a bead on a seal for a bushing, the combination of a body having means for securing said body to said bushing when the body is rotated relative to the bushing, a handle on said body, a latch between said body and handle causing the body to be rotated relative to the bushing and permitting the handle to 15 move relative to said body, a shaft secured to said handle and expanding means operated by said shaft to cause said expanding means to expand said seal when the handle is moved relative to the body secured in the bushing.

20 6. In a tool of the class described, the combination of a body, a stop secured to said body, a handle, expanding means carried by said body and operated by said handle, means for latching together and unlatching the handle 25 and body, said expanding means being operable when the handle and body are unlatched and said stop is effective.

30 7. In a tool of the class described, the combination of a threaded body adapted to be screwed into a threaded opening, a shoulder on said body, a shaft extending through said body, a handle carried by said shaft and adapted to rotate the tool as a whole and to rotate the shaft relative to said body, means 35 for connecting and disconnecting said handle and body, and means operated by said shaft for forming a bead.

40 8. In a tool of the class described, the combination of a threaded body adapted to be screwed into a threaded opening, a shoulder on said body, a shaft extending through said body, a handle carried by said shaft and adapted to rotate the tool as a whole and to rotate the shaft relative to said body, cam 45 means on said shaft, expandible segments carried by said body and operated by said cam means, and spring means surrounding parts of said segments for returning the latter to normal position.

50 55 In testimony whereof, I have subscribed my name.

JOHN W. SHERA.
